Application February 20, 1934, Serial No. 712,167

9 Claims. (Cl. 244—25)

Our invention relates to an aeroplane which may be driven in the conventional manner as by having engines operating propellers, or the like, and in which our improvement consists in 5 making use of the slip stream of air passing preferably along the fuselage of the aeroplane to operate auxiliary propellers. These auxiliary propellers are designed to be shiftable and may be used as helicopter propellers to increase the lift, 10 preferably when taking off from the ground and gaining altitude. Then, when the aeroplane is flying at the desired elevation, the auxiliary propellers may have their shaft rotated in an arc and then operated as driving propellers. 15 A further object and feature of our invention is incorporating with an aeroplane, one or more air driven rotors, these being positioned to be rotated by the slip stream of air passing preferably along the sides of the fuselage. 20 A further feature of our invention relates to connecting the air driven rotors to vertical shafts which lead through a housing to a position above and below the wings so that propellers operatively connected to the ends of these shafts may rotate clear of the fuselage and any construction 25 at the top or bottom of such fuselage. By this arrangement, when the propellers are in one position, that is, rotating on a vertical axis, they may act as lifting or helicopter propellers. 30 Another object and feature of our invention relates to a changeable drive for the propellers so that the propeller shafts may be vertical or turned to a horizontal position and still have a positive drive from the vertical drive shafts 35 driven in turn by the rotary air motors.

A further feature of our invention relates to control equipment for turning the propeller shafts through an arc in a vertical plane so that they may be shifted between the vertical and 40 horizontal positions. These controls are located convenient to the pilot so that the pilot may manipulate and determine the position of the auxiliary propellers.

A further feature of our invention relates to 45 the particular drive and connection between the vertical driven shafts and the driven propeller shafts which swing through the arc, and in this feature, the propeller shafts preferably have a non-rotatable end section which is keyed to a 50 control and supporting shaft, which shaft also carries the pull or thrust of the propellers. This supporting shaft may be rotated through an arc and thus vary the position of the auxiliary propellers. Each auxiliary propeller has a rotatable section of its shaft with a gear connected there-

to, which gear is driven by an idler preferably located on the supporting shaft, and this idler is driven by a gear on a vertical drive shaft connected to an air motor.

A further object and feature of our invention is using the air motors to actuate electric generators charging storage batteries, which batteries may be used to operate electric motors, in turn driving the auxiliary propellers. Preferably a motor generator may be used which would actuate these propellers through the medium of the air motor.

Our invention is illustrated in connection with the accompanying drawings, in which:

Fig. 1 may be considered as a horizontal section 15 through a portion of an aeroplane as taken substantially on the line 1—1 of Fig. 2 in the direction of the arrows.

Fig. 2 is a vertical transverse section on the line 2—2 of Fig. 1 in the direction of the arrows, 20 the shafts and gears on the section line being shown in elevation.

Fig. 3 is a vertical longitudinal section taken on the line 3—3 of Fig. 2 in the direction of the arrows, the shafts and gears on the section line 25 being shown in elevation.

Fig. 4 is an enlarged detail of the drive to the propellers on the section of Fig. 2, the shafts being illustrated in elevation.

Fig. 5 is a vertical longitudinal section taken 30 on the line 5—5 of Fig. 4 in the direction of the arrows.

Fig. 6 is a detailed horizontal section taken on the line 6—6 of Fig. 3 in the direction of the arrows illustrating an electric generator and motor 35 connection to the air driven motor.

Referring first to the construction of Figs. 1, 2 and 3, this shows a portion of an aeroplane fuselage 11 which has side portions 12, and a nose section 13. A transverse partition 14 divides the 40 fuselage into a pilot's compartment 15 at the front and a passenger cabin 16 rearwardly thereof. The pilot's seat is indicated at 17. The fuselage is illustrated as having a floor 18, a ceiling 19, a downwardly curved lower surface section 45 20, and an upwardly arched top section or roof 21. The fuselage may be of any desirable shape conforming to aeroplane practice and is preferably properly stream-lined.

The wings 22 extend laterally from the fuselage and in the illustration these are shown as of the monoplane type. The engines may be located at any suitable place but in the present instance the engines 23 are illustrated as mounted on wings, there preferably being one or more en-

gines on each wing and each engine operating a driving propeller 24.

With our design it is preferable not to use a propeller on the nose of the fuselage, but if desired, an engine with a drive propeller may be located on the top of the fuselage, this if desired, being the sole driving engine, or used with wing engines, or the aeroplane may have wing engines alone. These engines are of sufficient power to drive the aeroplane through the air and to adequately support the aeroplane after rising from the ground.

In our invention we utilize one or more air motors 25. These are illustrated as having a vertical opening 26 in the side wall 12 of the fuselage. Provision is made for four of these motors as illustrated in Fig. 1, and back of the opening there is a semi-cylindrical housing 27 which extends between the floor 18 and the ceiling 19. (Note Figs. 2 and 3.) A vertical air motor shaft 28 extends through the floor and ceiling where it has anti-friction bearings 29. (Note Fig. 3.) Keyed to each of these shafts there are two sleeves 30 each of which has a plurality of vanes or blades 31. Each sleeve has a shoulder 32 forming a shoulder abutment with each of the bearings. The shafts 28 each have a lower extension 33 below the floor and an upper extension 34 above the ceiling. It will be noted on reference to Figs. 1, 2 and 3 that the upper and lower set of vanes or blades are positioned out of alignment and that there are four blades on each unit. Also, the blades project through openings 26 beyond the side walls of the fuselage. It is desirable to have the shaft 28 as close to the side surface of the fuselage as possible to obtain a projection of the vanes or blades substantially equal to their radius. This is so that as large an amount as possible be exposed to the flowing air stream which flows around the nose surface of the aeroplane in the direction of the arrow 36 and along the sides of the fuselage in the direction of the arrow 37. This air stream flowing rearwardly causes the rotor of the air motor to rotate in the direction of the arrow 38, thus the air rotors on opposite sides of the fuselage rotate in an opposite direction.

The rotor shafts are used to drive vertical transmission shafts 39. These shafts are enclosed in upper and lower substantial housings 40 and 41, these housings being preferably stream lined and having a front section 42, and a rear section 43 (note Fig. 6), which serve as stream lining surfaces both front and rear. The upper housing extends above the top of the roof section 21 and has an outside skin 44 in alignment with the outside skin wall 12 of the fuselage. The inner surface 45 is also preferably parallel to the outside skin 44 and these merge into the front and rear portions 42 and 43. Where the sides 45 and front portions 42 and 43 merge into the roof 21 there is an opening 46. The lower housing 41 also has an outer skin 47 in alignment with the outer surface 12 of the fuselage, and an inner wall 48. These merge into the front and rear portions 42 and 43 and where these latter and the inner wall 48 merge with the lower section 20, there is an opening 49. These shaft housings are made sufficiently strong to properly support the various shafts and gears mounted thereon, but are no larger than necessary to accommodate the shafts and gears hereinunder detailed, so that the air resistance to these upper and lower housing projections 40 and 41 will be as little as possible.

Each of the housings 40 and 41 is provided with a gear box 50. (Note Figs. 2, 3, 4 and 5.) These gear boxes have end walls 51 fitted into sides of the housings 40 and 41, and are provided with an end wall 52 which forms an end closure for the 5 housings 40 and 41, and the front or rear wall 53, which merges into the upper front portion of these upper and lower housings. The walls 52 and 53 are merged into a curved corner 54 which has a slot 55 therethrough. (Note Figs. 4 and 5.) 10 An inner wall 56 connects the sides and front and rear portions of each of the upper and lower housings 40 and 41.

The manner of mounting each of the vertical transmission shafts 39 is as follows:

A bearing 57 is secured to the floor 18 and another to the ceiling 19 for each assembly. The walls 56 each have a journal 58 through which the shafts 39 extend, thus these shafts are journaled adjacent their opposite ends. The extensions 33 and 34 of the wind rotor shaft 28 have a gear 59 which meshes with a complementary gear 60 on each of the shafts 39 of each assembly. Thus, when the shaft 28 of the wind rotor is rotated due to the action of the slip 25 stream acting on the vanes, each of the vertical transmission shafts 39 is likewise driven.

The adjustable mounting for the propellers is as follows:

A supporting rock shaft 61 is mounted in anti-friction bearing 62 in the sides 51 of the gear box. (Note Fig. 4.) This has a series of splines 63 thereon which engages a hub 64 of the non-rotating section 65 of the propeller shaft designated by the assembly numeral 66. The non-rotating section 65 of the shoulder 67 has a bushing 68 which bears against this shoulder. A bevel gear 69 is rotatably mounted on the bushing. This gear has a square or some non-circular shaped socket 70 in which fits the squared end 71 of the rotatable section 72 of the propeller shaft, there being a collar 73 bearing on the end of an externally threaded sleeve 74 which forms a socket. A clamped nut 75 is threaded on the sleeve 74 and bears on the collar 73. This clamps the rotary section of the propeller shaft to the gear 69. The rotary section of the propeller shafts extends through the actuate slot 55 and has a propeller 76 secured thereto by key 77 or similar device. The shaft 61 has a bushing 78, (note Fig. 4), and on this bushing there is an idler gear 79 having two sets of teeth 80 and 81, these both being beveled in a different direction. The teeth 80 mesh with the gear 69. The bushing and gear are held in place by means of a shoulder 82 on the end of the bushing, a ring 83, washer 84, and nuts 85 threaded on a threaded section by a shaft 61. The gear is spaced from the hub 64 by means of washers 86. A washer 87 is on the opposite side of the hub and engaged by the nuts 88 at a threaded section of the shaft 61.

A drive bevel gear 89 is secured on the outer end of each of the vertical transmission shafts 39. This gear operates on a ball bearing 90 on a journal 58. It has a counter-sunk end 91 and is held in place by nuts 92 on a threaded end of the shaft 39. This gear 89 meshes with the teeth 81 of the idler gear 79. Therefore a power drive is transmitted from the rotor of the air motor through the gears 59 and 60, the vertical transmission shafts 39, and eventually to the auxiliary propellers.

The mechanism for shifting the auxiliary propellers from their position for vertical lifting as

shown in full lines in Figs. 2 and 3 to the dotted line position of Fig. 3 is as follows:

Each supporting shaft 61 is provided with an operating arm 93 secured thereto. This arm is provided with an eye 94 (note Figs. 4 and 5) to which is attached two ends 95 and 96 of an endless cable 97. This cable passes over a reversing pulley 98 secured to the wall 52 of the gear box and leads to a rotatable drum 99 in the pilot's compartment. (Note Figs. 1 and 3.) The cable may be secured to the drum in any manner, such as being attached by staples or having several turns. It is necessary to have a sufficient number of reversing pulleys to properly guide the endless cable. The drum is rotated by an arm 100 and located convenient to the pilot. The drum may be locked in any suitable position as by a brake or pawl and ratchet arrangement.

The cables from the upper and lower rock shafts 61 and their arms 93 lead to the same drum. In the illustration these cables extend to the drum from the rock shafts forming an operative assembly with the wind motors and propellers in front of and to the rear of the wings. Thus, it will be seen that by operating the drum all of the auxiliary propellers may be shifted from a rotation on vertical axes to rotation on horizontal axes or intermediate positions.

The auxiliary wind motors are operatively connected to drive electric motor generators designated by the assembly numeral 101. (Note Fig. 6.) There is preferably one generator for each wind motor. The drive may be in any suitable manner, and as illustrated, a pulley 102 or sprocket is secured to each of the shafts 28 of the wind motor rotors and drives by a belt 103 from a sprocket chain to the generator. The generator is connected by suitable electrical wiring 104 to a storage battery 105, one battery for all of the generators being sufficient. Thus, while the wind motors operate to actuate the generators, they in turn charge the storage battery.

These generators are of such a type that they may be used as driving motors and by suitable control by the pilot, the electric motors may be used to rotate the rotor of the wind motors and hence the auxiliary propellers. Thus the storage batteries may be drawn upon as a source of energy to aid the initial lift in rising from the ground, in which case the auxiliary propellers would be used as helicopters.

Another important feature of our invention in operation is that the auxiliary propellers may be used as helicopter lifters in landing in which case the motor generators would be used to rotate the rotors of the wind motors and hence the propellers. In this case, the auxiliary propellers would have their shafts in the vertical position. These auxiliary propellers could therefore also be used to obtain a safe landing if the main driving engines or propellers become inoperative, as the whole aeroplane could be lowered in safety when the four sets of auxiliary propellers are driven by their motor generators operating as electric motors.

In taking off from the ground the electric motors driving the auxiliary propellers operate as helicopters and may be used to increase the lift.

Various changes may be made in the details of construction without departing from the spirit or scope of the invention as defined by the appended claims.

We claim:—

1. An aeroplane having an engine with a propeller for propulsion through the air, a fuselage

having a vertical opening on one side with a housing inside thereof, a wind operated rotor having vanes, certain of said vanes extending outwardly through the opening beyond the side of the fuselage to be driven by the slip stream of air past the fuselage, a rock shaft, a propeller shaft having a non-rotatable section connected thereto to rock through an arc, the propeller shaft having a rotatable section with a propeller mounted thereon, and drive from the rotor to the rotatable section of the propeller shaft.

2. An aeroplane as claimed in claim 1, the drive to the rotatable section of the propeller shaft comprising a gear rotatable on the non-rotatable section of the shaft and coupled to the rotatable section of the propeller shaft.

3. An aeroplane having a motor with a propeller for propulsion through the air, a wind driven motor having a rotor rotated by the slip stream of air past the aeroplane, a shaft driven by the said rotor, a rock shaft, a propeller shaft having a non-rotatable section secured to the rock shaft whereby the propeller shaft may be rocked from a vertical to a horizontal position, the propeller shaft having a rotatable section coupled to the non-rotatable section by a gear, the said gear being rotatable on the non-rotatable section and means to drive said gear from the said driven shaft.

4. In an aeroplane as claimed in claim 3, the said gear having a socket, the rotatable section of the propeller shaft having a squared end fitting in said socket and a clamping nut securing the rotatable section to the said gear.

5. An aeroplane having an engine with a propeller for propulsion through the air, a fuselage having vertical sides with wings extending outwardly therefrom, four wind motors each having a vertical opening in the fuselage side and a partly cylindrical housing inside of the said opening, there being two wind motors on each side of the fuselage, one in front and one behind a wing, each wind motor having a vertical shaft located adjacent the side of the fuselage, each shaft having a plurality of radial vanes, certain of said vanes always projecting through the opening to be driven by the slip stream of air past the opening, an upper and a lower vertical shaft driven by each rotor shaft, a housing for each driven shaft having a rock shaft therein, each rock shaft having a propeller shaft connected thereto, the propeller shaft having a non-driven section attached to the rock shaft whereby each propeller shaft may be rotated from a vertical to a horizontal position, each propeller shaft having a gear rotatable on the non-rotatable section of the shaft and having a rotatable section connected to said gear, the rotatable section having a propeller attached thereto, an idler gear rotating on the rock shaft and meshing with the said gear, and a drive from each vertical shaft to each idler gear.

6. An aeroplane having a fuselage with an opening in its side, said opening extending vertically from a lower to an upper portion of the fuselage, an upper and lower housing connected respectively to the upper and lower portion of the fuselage, a wind motor shaft journalled in the fuselage and having wind motor vanes thereon, the said vanes in their rotation extending outwardly through the said opening to be engaged by the stream of air flowing past the fuselage, a transmission shaft in each of the housings and having a drive connection from the air motor shaft, the ends of each housing having a gear

box, a propeller having a propeller shaft, means to secure said shaft in the gear box, means for rotating the propeller shaft from a vertical to a horizontal position, and a gear drive from each transmission shaft to each propeller shaft.

5 7. An aeroplane having a fuselage with a vertical opening in the side, a wind motor shaft journaled in the fuselage and having air engaging vanes secured thereto, the said vanes on rotation extending through the opening to be operated by the air flow past the fuselage, a structure having a propeller mounting secured to the fuselage, the propeller mounting having a propeller shaft with a propeller, means to swing the propeller shaft between a horizontal and a vertical position, a transmission shaft actuated by the air motor shaft, and a gear drive between the transmission shaft and the propeller shaft, said gear drive being operative whether the propeller shaft is vertical, horizontal or in an intermediate position.

10 8. In an aeroplane as claimed in claim 7, the said gear drive comprising a bevel gear on the transmission shaft to rotate such shaft and a double bevel gear mounted on a shaft and en-

15 gaging a gear on the transmission shaft and on the propeller shaft.

9. An aeroplane having an engine with a propeller for propulsion through the air, a fuselage having a wind motor formed with a vertical opening in the fuselage side and a cylindrical housing inside of the said opening, a vertical wind operated rotor shaft at the center of the said housing and adjacent the side of the aeroplane, a plurality of radially extending vanes secured to the said shaft, certain of said vanes always projecting outwardly through said opening to be driven by the slip stream of air past the fuselage and a propeller having a propeller shaft, said propeller shaft being driven by the shaft of the 15 wind driven rotor, the propeller shaft having a rotatable and non-rotatable section being connected to a rock shaft, means to rock said shaft to swing the propeller shaft from the vertical to a horizontal position, and a gear drive between 20 the shaft of the wind driven motor and the rotatable section of the propeller shaft.

MICHIAL ASLANIAN.
DANIEL ASLANIAN.
